Atty's

UNITED STATES PATENT OFFICE.

JOHN M. YOUNG, OF BROOKLYN, NEW YORK, ASSIGNOR TO AMERICAN CAN COMPANY, OF NEW YORK, N. Y., A CORPORATION OF NEW JERSEY.

CONTAINER.

Application filed October 25, 1922. Serial No. 596,699.

My invention relates in general to cans of the tear-open type and more particularly to those in which a tearing strip is formed by score lines in the body beneath the top, and a separate collar, or neck member, provided on the interior of the can adapted to be secured to the body wall and to cover and extend above said score lines, providing a shoulder upon which the severed cover may be positioned as a slip closure.

A principal object of the present invention is the provision of a container of the character described wherein the resulting collar, or neck member, extends up beyond the tearing strip in liquid-tight connection with the material beneath it to prevent spilling of the contents when the tearing strip is removed.

A further object of the invention is the provision of an interior collar can of this character in which special sealing means is employed in addition to the frictional fit of the parts to form an effective and complete seal for the purpose stated.

Another object of the invention is the provision of a process of assembling cans of this character which results in a tighter joint between the collar member and can body than has heretofore been possible.

Other objects and advantages of the invention will be apparent as it is better understood from the following description, which, taken in connection with the accompanying drawings, discloses a preferred embodiment thereof.

Referring to the drawings,

Figure 1 is a side elevation, partly in section, of a container in which my invention is embodied;

Fig. 2 is a partial vertical section, somewhat enlarged, showing the interior of the can body prior to the positioning of the collar or supplementary wall part;

Fig. 3 is a similar section showing the interior collar and can cover assembled; and

Fig. 4 is an enlarged horizontal section showing the relative arrangement of the locking seams formed in the can body and collar and showing the cement in the spaces between said parts.

The can shown in the drawings for the purpose of illustration, comprises a body 11

having a bottom end 12 and a cover 13 secured thereto in a double seam 14, forming an hermetically sealed container. The body is of 55 cylindrical form, the edges of the body blank being joined in a side seam 15, which is formed on the exterior of the body wall so that a flush inner surface is presented for liquid-tight engagement with an interior collar, or a band 16.

Said collar has its edges joined in an inwardly extending seam 17, thus forming a flush outer surface adapted for tight frictional engagement with the inner surface of 65 the body wall.

The body is interiorly scored at 18 and 19 to set off a tearing strip 21, which is provided with a tongue 22 extending from a lapped portion of the side seam and adapted for engagement by a key for removal of the strip. Said strip is diagonally scored, as indicated at 23, to facilitate the tearing of the strip upon the lines 18 and 19, the tear being directed back to said line by this diagonal scoring in the event that, for any cause, it is directed away therefrom.

Upon opening a can of this character containing liquid extending above the level of the tearing strip score lines, there would be 30 danger of the contents spilling, with resultant loss and inconvenience to the consumer, unless prevented by the inner band or collar. I, therefore, provide means for obtaining a tight seal between said collar and the inner 35 face of the body, which prevents leakage of the liquid between said body and the lower part of the collar. The said collar 16, it will be understood, is secured beneath the tearing strip and extends thereabove to provide 40 a shoulder upon which the severed top of the can may be positioned as a slip closure. The formation of the body and interior collar, as heretofore described, permits a tight frictional fit between said members, which, in a 45 measure, may provide a liquid-tight seal. However, I prefer to employ other and, in a sense, supplementary sealing means, to insure against the premature running out of the contents. This not only obtains a more 50 perfect seal, but permits the use, if desired, of a collar fitting less tightly in the body, thus facilitating the positioning and removal of the severed top as a slip closure. To this

end, I distribute a band of cement, indicated by the stippled section 24 in Fig. 2, about the inner surface of the can body beneath the score line 19, which, upon forcing the collar 16 downwardly in the can, collects in a ring 25 at the lower edge thereof, and said cement positively secures the collar to the surface of the body, it being noted that said collar is turned inwardly at its lower edge 10 26 and also at the upper edge 27.

It sometimes occurs that there is a slight space, or crevice, indicated by the reference character 28, at the point of bend of the side seam 15, or the seam 17 in the collar and 15 when said collar is so positioned, this space is filled by cement, as shown in Fig. 4, and the seal between said parts thus rendered more effective.

An important result which I secure by 20 my invention is to insure an even and level severance of the tearing strip around the body on the line which is the bottom edge of the cover when the latter has been separated, so that the bottom edge of the depending 25 flange of the cover, which was in one piece with the body before severance, will not be jagged or outstanding or uneven.

Another important result is that I improve 30 the appearance of the can by scoring it internally, which is of especial benefit in the case of an externally lithographed can, and yet prevent access of the contents of the can to said scoring, and the deterioration of the can body thereby, by the arrangement of 35 the collar to cover said scoring and also to form a projection around which the severed cover may fit to form a reclosure.

It is thought that the invention and many 40 of its attendant advantages will be understood from the foregoing description, and it will be apparent that various changes may be made in the form construction and arrangement of the parts without departing from the spirit and scope of the invention, 45 or sacrificing all of its material advantages, the form hereinbefore described being merely a preferred embodiment thereof.

I claim:

1. A can, comprising a body internally 50 scored beneath the top to provide a tearing strip for removal of the top, and an internal collar covering the interior body scoring and secured in place by a cement band distributed about the inner wall of the container prior to 55 positioning of the collar and collected about the lower edge thereof to form a tight seal between the can body and collar and to fill in spaces therebetween after the collar is forced into the can to assembled position.

60 2. The process of assembling an internal collar in an hermetic container having internal score lines setting off a tearing strip beneath the top which comprises distributing a band of cement about the interior of the can 65 body beneath the lowermost score line and

forcing the collar downwardly in tight frictional contact with said interior surface, thus collecting a sealing ring of said cement at the lower edge of the collar and filling in irregular spaces between said collar and the inner 70 surface of the can body whereby said score lines are protected from the contents of the can.

3. The process of assembling an internal collar in an hermetic container having internal 75 score lines setting off a tearing strip beneath the top, which comprises distributing a band of cement about the inner surface of the can body beneath the lowermost score line and forcing a collar having an inwardly turned 80 edge downwardly in tight frictional contact with the container wall whereby a sealing ring is formed beneath and behind the turned edge of said collar.

4. A can, comprising a body having internal score lines beneath the top defining a tearing strip and having an outwardly extending side seam, and a separate collar member having an inwardly extending side seam and secured to the inner wall of the container 90 with a liquid-tight seal, said seal being formed by a band of cement distributed about the inner surface of the body wall beneath the score lines and collected at the edge of said collar member in assembling, said cement also filling spaces between the collar and can body occasioned by the formation of said seams. 95

5. The combination of a can body having its top edge outwardly flanged, and formed on its inner surface with scored lines extending around the body, and setting off a tearing strip at a distance below the top of the body and with other scored lines at angles to the setting-off scored lines, an interior collar fitting within the body opposite to said scored lines and tearing strip, said body extending in one piece of metal past said collar and above and below the same and having a locked side seam arranged on the outer side of the body so as to leave the interior of the body 100 smooth to be fitted by said collar, and the ends of said collar being united by a locked seam arranged at the inner side of the collar leaving the exterior of the collar smooth, a film of cement between the collar and the body below said tearing strip, and a flanged top end having its flange united in a double seam with the flange of the body. 105

6. A diagonal or herring-bone scoring to effect the formation of an even edge at the bottom edge of a can reclosure, said scoring being formed on the surface of a can body between upper and lower circumferential scorings, and combined with an internal collar fitting tightly within the can body opposite to 110 all of said scoring, whereby the tearing off of the scored portion of the can body produces an even bottom edge on the separated upper portion of the can body to fit over the upper 115 end of said collar as a reclosure. 120

7. A diagonal or herring-bone scoring to effect the formation of an even edge at the bottom edge of a can reclosure, said scoring being formed on the inner surface of a can body between upper and lower circumferential scorings, and combined with an internal collar fitting tightly within the can body and overlying all of said scoring, whereby the tearing off of the scored portion of the can body produces an even bottom edge on the 10 separated upper portion of the can body to fit over the upper end of said collar as a reclosure.

JOHN M. YOUNG.
